In Belgium June 6, 1947

8 Claims. (Cl. 19—109)

1

The present invention relates to an apparatus for cleaning the card clothing of the card cylinder of carding engines.

In my copending patent application Ser. No. 589,002, filed April 18, 1945, now Patent 2,481,002, issued September 6, 1949, I have described an apparatus for continuously preventing the clogging of the card clothing of the card cylinder of carding engines for cotton and other textile fibers. Said apparatus consists essentially of one or more suction nozzles or analogous devices mounted at a suitable distance such as 1 to 2 mm. from the teeth of the card clothing of the card cylinder and combined with supporting members which permit of a regular and gradual displacement of said nozzles in the one or other direction. One or more outlet conduits are provided for discharging the stripped material onto the feeding lap before it arrives at the feed cylinder of the carding engine. The apparatus is placed at the rear part of the engine above the cover of the licker-in in the space which remains between the licker-in and the curve formed by the flats, and comprises an electro-aspirator.

An object of this invention is to improve the apparatus hereinbefore described by increasing its efficiency and simplifying its construction, and to provide means for ensuring its proper and continuous operation.

Another object is to provide means for adjusting and fixing the suction nozzle in a suitable position.

Other objects and advantages will be apparent from a consideration of the specification and claims.

According to this invention the electro-aspirator of my copending application is replaced by a condenser of special construction, described hereinafter, communicating with a stationary aspirator controlled by the carding engine itself. Said condenser ensures an efficient operation for an unlimited period of time provided that slow motion is applied and that all the revolving parts are supported in bearings of plastic materials which do not require lubrication.

The suction nozzle may be provided with adjusting means, in combination with an also adjustable fixed stop, which facilitate its mounting at a suitable distance from the teeth of the carding cloth of the carding cylinder while preventing its direct contact with the teeth.

Other features of the invention may be noted from the following description made with reference to the accompanying diagrammatic drawings, showing by way of example an embodiment

2

In the drawings:

Fig. 1 is a diagrammatic view in side elevation of a condenser according to this invention, provided with a suction nozzle;

5 Fig. 2 is a partly sectional view in side elevation of the same condenser and suction nozzle, taken from a side opposite to that of Fig. 1, showing the gear box without its cover;

10 Fig. 3 is a view showing certain parts of the apparatus in vertical section on line III—III of Fig. 2;

Fig. 4 is a view showing the suction nozzle and associated parts in vertical section on line IV—IV of Fig. 3;

15 Fig. 5 is a partial view of some details of the apparatus shown in section on line V—V of Fig. 1.

The apparatus shown in the drawings consists essentially of a casing or body 1 having at its upper part a tubular or clamping element 2 embracing the supporting rod 3. This rod is arranged parallel to the axis of the carding cylinder in such a way that the apparatus may travel lengthwise of the carding cylinder in the one or other direction as described in my copending application Ser. No. 589,002. The rod 3 is provided with a double thread in which the guiding fork 4 engages under the action of a spring 5. The whole rod 3 is protected against dust by a cover 6 (Figs. 2 and 4).

30 Inside the casing or body 1 a drum 8 is mounted upon a shaft 7. The drum 8 is divided, by means of radial walls, in a desired number of compartments 9, for instance eight according to the illustrated example (Fig. 4). The cylindrical surface of the drum 8 is provided with groups of fine radial perforations. The drum is pressed in axial direction by a spiral spring 14 against the smooth wall 12 of a suction chamber 13 and is driven from the shaft 7 by means of a feather 15. The wall 12 is provided with a suction port 16, which

35 opens the suction chamber 13 to preferably two compartments 9 of the drum 8, and the suction chamber 13 communicates with a stationary suction source, mounted beside the carding engine, through the outlet 43 (Fig. 1). The box constituting the suction chamber 13 is secured to the casing 1 of the apparatus by means of set screws 17 and is provided with a detachable lid 18. At the end opposite to the suction chamber, the drum has a flange or packing ring 19 of leather or other material, which is located in a corresponding annular groove of the casing 1. An effective seal of the drum 8 is secured at its lower part by a flat or leaf spring or a resilient hoop

40 20 and at its upper part by a fluted roller 21 to which a flat or leaf spring 22 of steel is applied.

The roller 21 is mounted on a shaft 23, which is rockingly or oscillatingly carried by the free ends of two supporting levers 24' and 24'' the other ends of which are pivoted to the fixed shaft or cross bar 25. The ends of the roller 21 fit between the walls of the body 1 of the apparatus and in order to maintain a good seal the roller is provided inside with an axially slid able member 26 which, under the action of a spiral spring 27, is pressed against the adjacent wall of the casing 1 (see Fig. 5).

The perforated drum 8 is driven from the supporting rod 3, which rotates during the operation of the apparatus, in the following way: Before or behind the clamping member 2 a pinion 28 is arranged which engages with an inner pin 29 a longitudinal groove provided in the rod 3; when the pinion 28 is driven by the rotation of said rod it transmits said rotary motion to the toothed wheel 30. This toothed wheel 30, mounted on shaft 31, is fixed to a pinion 32, which meshes with a toothed wheel 33 secured to the shaft 7 of the drum 8. The toothed wheel 33 has a second toothed rim 34 the deep teeth of which mesh with the corresponding teeth of the pinion 35 mounted on the rock shaft 23 of the roller 21 (see Figs. 2 and 3). The whole gear mechanism is mounted inside a chamber of the body 1, said chamber being hermetically closed by a lid 36.

The suction nozzle comprises the mouthpiece proper 37, which after an initial tapering of the inner diameter flares conically and communicates with the inside of the body 1. Said mouthpiece 37 is united with a molded plastic member 38 having a threaded cylindrical surface, which permits of screwing it into the corresponding part of the body 1 and of exactly adjusting the nozzle; a lock-nut 39 is provided for fixing the nozzle in position.

The nozzle is combined with a stop-rod 40, which itself is adjustable in a boss 41 provided at the lower part of the body 1 and may be secured in a position ensuring a suitable constant distance of the nozzle from the card clothing by means of fixing nuts 42.

With the apparatus thus described the operation is as follows:

It is mounted at the carding engine like the apparatus described in my copending application Ser. No. 589,002, i. e. on a suspension rod 3 placed at the rear end of the carding engine above the hood of the licker-in and in the space between the licker-in and the curve formed by the flats; the nozzle 37 passes through a slot provided in the cover of the carding cylinder and is adjusted by means of a nut 38 and lock-nut 39 and a stop-rod 40, which co-operates with said cover itself, in such a way that the nozzle is held at a convenient distance from the teeth of the carding cloth of the carding cylinder. The pipe 43 is connected by a flexible pipe or similar means with a stationary aspirator, which is mounted beside, and driven by, the carding engine proper.

The apparatus mounted as described hereinbefore is traversed alternately in the one or other direction along the supporting rod 3 when the latter is rotated, as described in my copending application Ser. No. 589,002. The rotary motion is transmitted over the gears 28, 30, 32, and 33 to the perforated drum 8 and from said drum over the toothed wheel 34 and pinion 35 to the fluted rocking roller 21. On the other hand, the suction chamber 13 communicates with a stationary aspirator which produces a vacuum in said chamber; through the port 16, the adjacent

compartments 9 of the drum 8 and the corresponding perforations 11 said vacuum brings about a suction in the interior of the body 1 and therefrom in the head of the nozzle 37. Accordingly, a part of the fibers which are in front of the nozzle 37 on the carding cloth of the carding cylinder will be sucked in the body 1, adhere onto the revolving drum 8 and move with said drum in the direction of the arrow indicated in Fig. 4 towards the rocking roller 21, which catches them under the action of the spring 22 and expels them to the outside. This expulsion is facilitated by the fact that the compartments 9 of the drum 8, before passing through a plane determined by the axes 7 and 23 of the drum 8 and roller 21 respectively, are blanked off the suction port 16 and remain, therefore, without direct communication with the suction chamber 13. The fibers caught between the drum 8 and the roller 21 serve at the proper time as a packing sealing off the inside of the body 1; on leaving the apparatus they pass through a pipe or over an inclined plane or simply fall down in form of a sliver upon the lap fed to the carding engine. The dust, which might enter through the perforations 11 into the compartments 9 of the revolving drum 8, passes to the aspirator and is separated by this way from the useful fibers, which are returned to the feed cylinder. It will be observed on an inspection of Fig. 4 that the radial perforations 11 of the drum 8 are arranged asymmetrically with respect to the middle axial plane of each compartment 9 in order to prevent the entry of air through said perforations when the respective compartment 9 is in front of the expelling roller 21.

I claim:

1. An apparatus for preventing the clogging of the card clothing of the card cylinder of carding engines having a suction nozzle mounted on a nozzle-carrying body for entering a slot provided in, and extending lengthwise of, the cover of the carding cylinder at the rear part of the carding engine in the space between the licker-in and the curve formed by the flats, means for supporting said body, and means for reciprocating it lengthwise of the carding cylinder, said nozzle-carrying body including a suction chamber communicating with a source of suction outside said body, a revolving drum divided by radial walls into longitudinal compartments and provided on its cylindrical face with a group of radial perforations for each of said compartments, means for pressing one end of said drum against the wall of said suction chamber, a suction port in said wall extending over a sector corresponding to at least one compartment of said drum, a sealing packing at the other end of said drum, means for sealing the space between the lower part of said drum and the wall of said body, a rotatable roller mounted for rocking movement, and means for pressing said roller against the surface of the drum for the purpose of compacting the fibers collected on said drum and expelling them.
2. An apparatus as claimed in claim 1 wherein the expelling roller is mounted on a rock shaft supported by the free ends of two supporting levers which at their other ends are pivoted to a fixed cross bar.
3. An apparatus as claimed in claim 2 comprising an axially slid able member located in an axial aperture of the expelling roller and spring means pressing said member against the adjacent wall of the body for obtaining a substantially tight seal.

4. An apparatus as claimed in claim 1 comprising a supporting rod for the nozzle-carrying body, a longitudinal groove provided in said supporting rod, a pinion provided with an inner pin engaging said groove, a gear mechanism transmitting the rotary motion of said pinion to the drum, a chamber for housing said gear mechanism, and means for hermetically closing said chamber.

5. An apparatus as claimed in claim 1 wherein the suction port is so located in the wall of the suction chamber that the compartments of the perforated drum clear said port before they move out of the interior of the body on rotation of said drum, and that direct communication with the suction chamber is cut off before they pass through a plane determined by the axes of the drum and the expelling roller.

6. An apparatus as claimed in claim 1 comprising a suction nozzle the inner diameter of which is first narrowed and then widened towards the suction conduit, and means for adjusting the position of the nozzle in the nozzle-carrying body.

7. An apparatus for continuously cleaning the card clothing of the carding cylinder of a carding engine comprising a suction nozzle and a body carrying said nozzle and adapted to be reciprocated lengthwise of the carding cylinder, said body containing a perforated rotating drum divided by radial walls into axially extending com-

partments, means for rotating said drum, the compartments of said rotating drum communicating successively with a source of suction, a roller yieldingly mounted in contact with the cylindrical surface of said drum for the purpose of continuously removing fibers collected thereon, a suction conduit between the suction nozzle and the drum, and sealing means for approximately confining the suction to the suction chamber and the parts communicating therewith within said body.

8. An apparatus as claimed in claim 1 wherein the rotatable expelling roller has a longitudinally fluted surface.
